UNITED STATES PATENT OFFICE

150,772

DESIGN FOR A COMBINED NAPKIN AND
COASTER TRAY

Walter K. Jahn, Beverly Hills, Calif., assignor to New Plastic Corporation, Los Angeles, Calif.,
a corporation of Delaware

Application September 25, 1946, Serial No. 133,557

Term of patent 3½ years

(Cl. D44—10)

To all whom it may concern:

Be it known that I, Walter K. Jahn, a citizen of the United States, residing in Beverly Hills, in the county of Los Angeles, State of California, have invented a new, original, and ornamental Design for a Combined Napkin and Coaster Tray, of which the following is a specification, reference being had to the accompanying drawing, forming a part thereof.

Fig. 1 is a perspective view of a combined napkin and coaster tray showing my new design.

Fig. 2 is a bottom plan view thereof.

I claim:

The ornamental design for a combined napkin and coaster tray, as shown.

WALTER K. JAHN.
